REGISTERING DEVICE FOR MULTICOLOR PRINTING

Frederick Shurley, Windsor, Ontario, Canada, assignor to Guthrie Ceramic Labelling & Machinery Co. Inc., Dover, Del., a corporation of Delaware

Application February 14, 1939, Serial No. 256,308

13 Claims. (Cl. 101—124)

This invention relates to improvements in registering devices for multicolor printing.

It is an object of the invention to provide a registering device for multicolor printing whereby the articles to be printed are rotated until they assume the desired rotary position for commencement of the printing operation and are then gripped and held immovable during their passage from registering to printing position and until commencement of the printing operation actually occurs, thereby eliminating the possibility of any slight rotary movement of the work that otherwise might take place, particularly if the weight of the article to be printed is slightly unevenly distributed, between registration and the commencement of the printing operation.

Another object of the invention is to provide a registering device for multicolor printing wherein a printing frame is reciprocated for printing and is moved substantially at right angles from its path of travel as it approaches each extremity of its stroke; and wherein means coact with the printing frame for releasing the grip upon the article to be printed as the frame is returned to its position for reciprocation thereby permitting the article to rotate freely in contact with the frame.

A further object of the invention is to provide such a registering device including a special electric control means by which the articles are successively registered and held immovable, which electric control means is cut out by movement of the frame back to its position for reciprocation.

Having thus briefly and broadly stated some of the objects and advantages of the invention I will now proceed to describe an embodiment thereof with the aid of the accompanying drawings, in which:

Figure 1 illustrates a side elevation of the invention and a portion of a printing machine to which it is applied.

Figure 2 is an enlarged sectional view taken on the line 2—2 of Figure 1, and

Figure 3 is an enlarged section on the line 3—3 of Figure 1.

Figure 4 is a wiring diagram.

Referring to the drawings, 1 designates a portion of a stand of a conventional printing machine upon which a carriage 2 is reciprocated by a connecting rod 3 mounted upon a crank 4 on a shaft 5 which is turned in any preferred manner—not shown. Mounted on both sides of the stand 1 are lugs 6 in which opposed pairs of stops 7 are provided. Carried by the carriage 2 are two parallel rods 8 the axial alignment of which coin-

cide with the direction of movement of the carriage. Formed in the rods 8 are cam slots 9 to receive the lower extremities of pins 10 which extend downwardly from a printing frame 11, which is supported by the carriage for reciprocation therewith. As the carriage approaches each extremity of its travel the rods 8 strike one pair of stops 7 and consequently their continued movement with the carriage is arrested. Then continued movement of the pins 10 with the printing frame 11 and carriage 2 moves the said pins out of the cam slots 9 and raises the frame 11. As the carriage and frame commence their return stroke and the rods are moved away from the stops 7 balanced springs 12 provided around the extremities of the rods return the latter to their normal positions with respect to the carriage 2 and pins 10 shown in Figure 1. The pins then drop back into the cam slots 9 and the printing frame 11 is again lowered to its normal printing position. Fixed on the stand 1 is a suitable switch 34 having an upwardly extending operating arm 35 laterally from which a roller 36 projects which rests upon the top of the frame 11. Consequently as the latter is raised and lowered the switch is actuated by movement of the arm 35 in a manner hereinafter described.

Mounted upon the stand 1 and extending transversely of the path of movement of the carriage 2 and beneath the latter is a shaft 15 mounted for intermittent rotation as shown in my co-pending application Serial No. 219,014. Fixed upon the shaft 15 are two opposed carrier plates 16 and 17. Radially mounted upon the carrier 16 are a plurality of chucks 18 which are inwardly urged by springs 19, and mounted upon the carrier 17, each opposite one of the chucks 18, are other chucks 20. Each opposed pair of chucks 18 and 20 are intended to support an article A to be printed, moreover the chucks and the article between them are normally free to turn so that the said article may be rotated to the position it is to assume for commencement of the printing operation. Extending axially from each chuck 20 is a spindle 21 which extends through an electro-magnet 22 carried by the carrier plate 17, and held against independent rotation upon the spindle 21 is a brake plate 23 which is drawn against the electro-magnet when the latter is energized, thereby arresting rotation of the chuck 20 and the article one extremity of which is supported thereby. Since the construction of the chucks 20, the electro-magnets 22 and the various coacting parts has already been fully described in my co-pending application above referred to it

is not believed necessary to further describe this portion of the structure.

Provided around the outer periphery of the carrier 17, and preferably supported in annular insulated grooves formed therein, are two parallel sets of segmental contacts 24 and 25. Each segment of each set extends through substantially 90° and around like portions of the carrier periphery, by which I mean that the ends of the segments of the two sets are disposed in transverse alignment. Suitably mounted upon a bracket 26, supported by the stand 1, are brushes 28 and 29 which wipe the segments 24 and 25 respectively in turn as the carrier 17 rotates, and mounted upon a similar bracket 27 are brushes 30 and 31 which also wipe the segments 24 and 25. Between adjacent pairs of segments 24, or 25, insulation 32 is provided by which each adjacent pair of segments is sufficiently spaced that no brush can be in contact with more than one segment at a time. Each of the segments 24 is connected with one extremity of the winding of one of the electro-magnets 22, and each opposed segment 25 is connected to the opposite extremity 25 of the winding of that magnet by connections 33 and 37 respectively.

Supported for rotation by the stand 1 is a stub shaft 38 having a friction disc 39 thereon which contacts the periphery of each chuck 20 in turn when the latter reaches a predetermined position and rotates it when it is free to turn. The shaft 38 is provided with suitable means for rotating it as for instance a sprocket wheel 40 over which a chain 41 passes which is driven from any suitable source—not shown.

Mounted on the stand 1 is a bracket 44 which carries a phototube 42, and suitably supported, as from the shaft 15, is a light source 43. When an article A supported between two chucks 18 and 20 is so positioned that its chuck 20 is in engagement with the friction disc 39 it is interposed between the phototube 42 and the light source 43, so that when the said article or bottle A has been turned by the disc to its desired rotary position an electric circuit about to be described is closed through a phototube relay, and the magnet 22 which cooperates with that chuck 20 by which one extremity of the article is held is energized; then further rotation of that chuck and the article held thereby is prevented.

I will now describe my electrical control means with the aid of the wiring diagram shown in Figure 4.

The electrical system consists of the following parts already mentioned, namely the phototube 42, the switch 34, the electromagnets 22, the segmental contacts 24 and 25, and the brushes 28, 29, 30 and 31; and in addition the amplifying tubes 45 and 46, a thyratron or other gaseous tube 47, resistors 48, 49, 50, 51, 52, 53, 54, 55 and 56, condensers 57 and 58, a voltage regulator tube 59, sources of power 60 and 60a, a neon tube 61, and potentiometers 63 and 64.

The phototube 42 is connected by a lead 70 to the grid of the amplifying tube 45, and a lead 71 extends from the plate of the latter to the grid of the second amplifying tube 46. From the plate of this second amplifier a lead 72 extends through the condenser 57 and resistor 56 to the grid of the gaseous tube 47. From the cathode of the latter a lead 73 extends to the binding post G and from the post a lead 74 is connected to one side of the switch 34. The opposite side of this switch is connected by a lead 75 to the binding post C and from this lead a wire 75a also extends to the

brush 29 which wipes the segmental contacts 25 as the carrier 17 rotates. The brush 28 which is in the circuit with the brush 29 is connected to the latter through each of the electro-magnets 22 in turn as the shaft 15 turns. From the brush 28 a lead 76 extends which is connected to the binding post D and from the latter through leads 77 and 99 and through the resistor 52 to the negative side of the source of power 60; and another lead 78 extends from the post D to the neon tube 61.

The brush 30 which wipes the segmental contacts 24 is connected by a lead 79 to the binding post F and from the latter by a lead 80 to the resistor 50 and from the latter through leads 80a 15 and 99 also to the negative side of the source of power 60. The brush 30 is connected through one of the magnets 22 to the brush 31; from the latter a lead 81 extends to the binding post E. This binding post is connected by a lead 82 to the 20 plate of the gaseous tube 47. The binding post G is connected by a lead 83 to the positive side of the source of power 60 and also to the adjustable resistor 55, and from the latter a lead 84 extends through the resistor 51 to the lead 10. From this 25 lead 84 a connection 84a is made to the potentiometer 63 and a second connection 84b to the cathode of the voltage regulator tube 59. The plate of this tube is connected at 85a to a lead 85 which extends from the phototube 42 to a 30 lead 86 connecting the adjustable resistor 55 with the potentiometer 63. From the lead 84, which is grounded to the casing of the instrument as indicated at 87, a lead 88 extends to the negative side of the source of power 60a. The cathode of the tube 45 is connected to the adjustable resistor 64 through a lead 89. A lead 90 extends from the lead 71 through the resistor 54 to a lead 91 which connects the lead 72 through the resistor 48 to the positive side of the source of power 60a. The 40 lead 91 is also connected at 91a to the potentiometer 63. The neon tube 61 is connected to the binding post C by a lead 93. The cathode of the amplifying tube 46 is connected by a lead 94 to the potentiometer 63. The lead 72 between the 45 condenser 57 and the resistor 56 is connected to the resistor 49 by a lead 95; this latter resistor being grounded as shown at 97 to the casing of the instrument. The lead 82 is connected by a wire 96 to the lead 73, and in the wire 96 immediately of its length the condenser 58 and resistor 53 are interposed. The binding post H is grounded to the casing of the instrument at 98.

The operation is as follows: When the phototube 42 is exposed to increasing light its internal 55 resistance decreases thereby causing the potential on the grid of the amplifying tube to become more positive, this increases the current in the plate of the tube 45 and through the leads 71 and 90 so that the grid of the tube 46 becomes 60 less positive, resulting in a reduction in the current through the lead 72 and thereby making the side of the condenser 57 connected to the lead 72 more positive. The reaction of the condenser 57 to this change in potential makes the grid of 65 the gaseous tube 47 more positive and "fires" this tube causing it to act as a relay and energize one of the electro-magnets 22 by allowing current to flow from the power supply 60 through the leads 99, 80a, 80 and 79, the resistor 50 and the binding post F to the brush 30; and from the brush 31 through the leads 81, and 82, post E, and the plate and cathode of the gaseous tube 47, leads 73 and 83, binding post G and back to the source of power 60. When this occurs one of 75

the chucks 20 is held immovable by its magnet 22. The carriers 16 and 17 holding the chucks 18 and 20 are then ready to be rotated through 90° to bring the work to its printing position. As rotation of the carriers occurs the switch 34 is closed by upward movement of the printing frame 11 which brings the switch contacts 34a and 34b together.

The closing of this switch closes a circuit beginning with the negative side of the source of power 60, through the lead 99, resistor 52, lead 17, binding post D, lead 76, brush 28, through one of the magnets 22, brush 29, leads 75a and 75, switch 34, lead 74, binding post G, lead 83 and to the positive side of the source of power 60. When rotation of the carrier 17 occurs the segments 24 and 25 energized through the brushes 30 and 31 also come into contact with the brushes 28 and 29 respectively. Then short circuiting of the brushes 29 and 31 by one of the segments 25 extinguishes the gaseous tube 47, thereby cutting off the supply of power through that tube, but as the brushes 28 and 29 are directly supplied with power from the source 60 so long as the switch 34 remains closed the magnet 22 between these brushes remains energized until rotation of the carrier 17 has ceased, and a downward movement of the printing frame 11 causes the switch 34 to open. Then of course the circuit is broken, and the chuck 20 in conjunction with which that magnet 22 operates is again free to turn.

When the switch 34 is opened there is an induced potential from the magnet 22 which would cause a destructive arc were this magnet not then connected to the neon tube 61 through the brush 29, lines 75a and 75, binding post C and the lead 93, and through the brush 28, lead 76, binding post D, and lead 78. This tube limits the voltage to a low value and avoids the destructive arc that would otherwise occur, and also eliminates disturbances to other parts of the electrical system which might cause undesired "firing" of the gaseous tube 47 by which one of the magnets 22 which has just come into contact with the brushes 30 and 31 would be energized. Similarly the wide spacing of the adjacent segments 24, or 25, is necessary for the same reason.

The operation is briefly as follows: After the carriers 16 and 17 have been turned so that the work A carried by an opposed pair of chucks 18 and 20 is positioned between the phototube 42 and the light source 43, the chuck 20 and the work are rotated by the disc 39 until the work reaches such a rotary position that light, from the source, of increasing intensity reaches the phototube. Then a circuit is completed through the brushes 30 and 31 and the electro-magnet 22 connected to the segments 24 and 25 with which the said brushes 30 and 31 respectively are in contact. Rotation of the work is then immediately halted by the brake plate 23 carried by the spindle 21 which is then drawn into intimate contact with the magnet. As the carrier 17 is turned to move the work to printing position upward movement of the printing frame 11 closes a circuit through the brushes 28 and 29 and the same magnet 22. This short circuits the gaseous tube 47 and breaks the circuit through the brushes 30 and 31, however the same magnet remains energized through the brushes 28 and 29 until the work has arrived at its printing position and the frame 11 is again lowered to its position for reciprocation immediately prior to its next printing stroke. By the lowering of the frame the switch

34 is opened and the circuit through the brushes 28 and 29 broken, so that the work about to be printed is again free to rotate in contact with the frame during the printing operation.

While in the foregoing the preferred embodiment of the invention has been described and shown it is understood that alterations and modifications may be made thereto provided the said alterations and modifications fall within the scope of the appended claims.

What I claim is:

1. A registering device of the character described comprising a carrier mounted for intermittent movement, a chuck rotatably mounted on said carrier and adapted to be moved to a registering position and from the latter to another position by movement of the carrier, said chuck being adapted to engage work, means tending to rotate the chuck and work when the latter are in registering position, an electrically operated brake mechanism on the carrier to coact with the chuck and halt its rotation, an electric circuit, means for including the brake mechanism in the circuit when the chuck is in registering position, means adapted to close said circuit when the work has been turned to a predetermined position, a second electric circuit, and means for including said brake mechanism in a second circuit during the movement of the chuck and work from said registering to said other position.

2. A registering device of the character described, comprising the combination set forth in claim 1, wherein means are provided for continuing the first circuit through a portion of the second circuit when the latter is closed.

3. A registering device comprising the combination set forth in claim 1, wherein a portion of the first circuit is short circuited by the closing of the second circuit to prevent a spontaneous re-establishment of the first circuit.

4. A registering device comprising the combination set forth in claim 1, wherein a printing frame is mounted for reciprocating movement in timed relation to the carrier, and means coacting with the frame for opening and closing the second circuit at each extremity of the frame stroke.

5. A registering device comprising the combination set forth in claim 1, wherein automatic means operated in timed relation with the intermittent movement of the carrier are provided for opening and closing the second circuit.

6. A registering device comprising a printing machine, a printing frame mounted for reciprocation thereon, means for moving the frame angularly to its path of reciprocation at at least one extremity of its travel, a carrier mounted for intermittent movement, a chuck mounted for rotation on said carrier and adapted to engage work, an electrically operated braking mechanism on the carrier adapted to coact with the chuck and hold the work and chuck against rotation, an electric circuit, means for including the electric operating means for the brake mechanism in said circuit during a portion of the carrier travel, a switch in said circuit and a movable operating arm on said switch having means for engaging said printing frame whereby angular movement of the latter operates said switch.

7. A registering device comprising a printing machine, a printing frame mounted for reciprocation thereon, and means for moving the frame angularly to its path of reciprocation at at least

- one extremity of its travel, in combination with a carrier mounted for intermittent rotation, a plurality of chucks mounted on said carrier for rotation, an electrically operated brake mechanism on said carrier to coact with each chuck, an electric circuit, means connecting each brake mechanism with said circuit in turn as the carrier rotates, and means operated by the angular movement of the printing frame for opening and closing said circuit.
8. A registering device comprising a carrier mounted for intermittent rotation, a plurality of chucks rotatably mounted on the carrier, each chuck being adapted to engage an article and to be moved successively into registering position by movement of the carrier, means tending to rotate each chuck and article when in registering position, an electrically operated brake mechanism to coact with each chuck and arrest its rotation, an electric circuit, means for including in the latter the electrically operated brake mechanism coacting with each chuck as each chuck in turn is moved into registering position, means for closing the circuit when the article to be registered has reached a predetermined rotary position, a second electric circuit, and means for including the brake mechanism in the first circuit in said second circuit to hold the chuck immovable during the ensuing movement of the carrier.
9. A registering device comprising a carrier mounted for intermittent rotation, a plurality of chucks rotatably mounted on the carrier, an electrically operated brake mechanism to coact with each chuck and mounted on said carrier, an electric circuit, means connecting each brake mechanism successively with said circuit as the carrier turns and said chuck reaches a registering position, means for closing said circuit when the chuck has reached a predetermined rotary position, a second electric circuit, means for including the brake mechanism in the first circuit in said second circuit during the subsequent movement of the carrier, and means opening the first circuit when the second circuit is closed.
10. A registering device of the character described comprising a carrier mounted for rotation, a plurality of chucks rotatably mounted on the carrier, an electrically operated brake mechanism to coact with each chuck, an electric circuit, means for connecting each brake mechanism successively with said circuit as the carrier

turns, a second electric circuit, and means for including the brake mechanism in the first circuit in the second circuit during subsequent rotation of the carrier through a predetermined angle.

11. A registering device comprising a carrier mounted for intermittent rotation, a chuck rotatably mounted on the carrier and adapted to be moved to a registering position and from the latter to another position by the carrier rotation, said chuck being adapted to engage work, means tending to rotate the chuck and work when in registering position, an electrically operated brake mechanism to coact with the chuck and halt its rotation, an electric circuit, means for including the brake mechanism in the circuit when the chuck is in registering position, a phototube relay for closing the circuit when the work has been turned to a predetermined rotary position, a second electric circuit, and means for including said brake mechanism in said second circuit during the next movement of the carrier.

12. In a registering device, the combination of a carrier mounted for intermittent rotation, a plurality of rotatably mounted chucks on the carrier, each chuck being adapted to be moved in turn to a registering position by the carrier rotation, an electrically operated brake mechanism to coact with each chuck, means tending to rotate each chuck when it reaches its registering position, spaced segmental contacts supported by said carrier and insulated therefrom, said contacts being connected to said braking mechanisms, two sets of brushes wiping said contacts as the carrier turns, two electric circuits each including one pair of brushes, and means for closing one circuit to arrest rotation of each chuck in turn at a predetermined rotary position when in registering position, and said other circuit including the braking mechanism by which said arrested chuck is held during the ensuing movement of the carrier.

13. In a registering device, the combination set forth in claim 12 wherein a switch is provided in the second circuit, and means operated in timed relation with the carrier movement for opening and closing said switch, the first circuit being adapted to be opened while the second circuit is closed.

FREDERICK SHURLEY.
